UNITED STATES PATENT OFFICE.

HENRY SLETTEN AND ALEXANDER N. LIDELL, OF MINNEAPOLIS, MINNESOTA.

DEVICE FOR SINKING FOUNDATION-TUBES.

1,154,137.

Specification of Letters Patent. Patented Sept. 21, 1915.

Application filed June 12, 1914. Serial No. 844,670.

To all whom it may concern:

Be it known that we, HENRY SLETTEN and ALEXANDER N. LIDELL, citizens of the United States, residing at Minneapolis, in the county of Hennepin and State of Minnesota, have invented certain new and useful Improvements in Devices for Sinking Foundation-Tubes; and we do hereby declare the following to be a full, clear, and exact description of the invention, such as will enable others skilled in the art to which it app pertains to make and use the same.

Our invention has for its object to provide a simple and highly efficient apparatus for use in sinking foundation tubes, through quick sand, or in doing similar work; and to such ends, generally stated, the invention consists of the novel devices and combinations of devices hereinafter described and defined in the claims.

In the erection of heavy buildings, bridge piers, and the like, it is customary to sink metallic foundation tubes into the ground until a rock bottom is struck. Such tubes vary in size from a few feet to many feet in diameter and are usually made in sections, which sections are connected together in the process of forcing the said tubes into the ground.

Our invention provides efficient means for boring through the ground by continuous operation, and for removing the loosened dirt and carrying the same upward and out of the tube, also, by a continuous operation, which is simultaneous with that of boring.

The apparatus may take various forms and one form thereof, is illustrated in the accompanying drawings, wherein like characters indicate like parts throughout the several views.

Referring to the drawings: Figure 1 is a view partly in elevation and partly in vertical section illustrating the apparatus as used for boring and sinking the foundation tubes; Fig. 2 is a vertical section taken through the lower portion of one of the tube sections and showing the boring device applied thereto; Fig. 3 is a plan view of the parts shown in Fig. 2; Fig. 4 is a plan view of the boring tool; and Fig. 5 is a side elevation of the said boring tool.

The sections 1 of the foundation tube are

adapted to be coupled together in different ways, as, for example, by means of coupling sleeves 2. The sectional tube is passed downward through a larger feeding and guiding sleeve 3, which, as shown, has threaded engagement with the surrounding portion 4 of a heavy foundation casting or base 5. The said sleeve 3 is provided with a projecting flange 6 preferably having radial peripheral perforations into which a bar may be inserted to rotate the said sleeve. The lower and upper ends of the sleeve 3 are arranged to bear, respectively, against heavy thrust collars 7 and 8, that are movably secured on the upper section of the tube 1 by set screws 9, or other suitable devices. With this arrangement, as is evident, the sleeve 3 will guide the sectional foundation tube 1, and when the said sleeve is screwed downward against the collar 7, it will force the said tube downward, and on the other hand, when the said sleeve 3 is screwed upward against the upper collar 8, it will raise the said tube 1 bodily. The downward movement is required in sinking the tube, while the boring tool, presently to be described, is in action. The upward movement of the said tube is sometimes necessary, either to remove a tube section or to permit a more ready removal of a rock in the path of movement of the said tool.

The boring tool, which is preferably employed, is of novel construction and has cutting blades or plows arranged, when the tool is rotated backward, to be moved radially inward within the interior diameter of the foundation tube, and to be forced outward, when the boring tool is rotated in an operative direction, so that the said movable blades or plows will project outward beyond the lower end of the foundation tube, and thus caused to bore a hole of somewhat greater diameter than the said tube. As best shown in Figs. 4 and 5, this boring tool comprises an upright shaft 10 having radial arms 11, which, on their front edges are beveled, so that they assist in the cutting action. To the said arms 11 are pivoted cutting blades or plows 12, which, when turned outward into operative positions, as shown by full lines in Figs. 4 and 5, project beyond the said arms for

the purposes above indicated, and which, when turned inward, as indicated by dotted lines in Fig. 4, are adapted to be moved upward or downward through the said foundation tube. When the plow blades 12 are turned outward, they strike against stop shoulders formed on the arms 11, as best shown in Fig. 5. The said arms 11 are preferably provided with fixed plow blades 13 located radially inward of the pivoted plow blades 12.

The shaft 10 is journaled in the upper and lower heads of a boring frame 14 that fits within the lower portion of the lower tube section and carries on its top an electric motor, the casing of which is indicated by the numeral 15 and an armature shaft of which is indicated by the numeral 16. The armature shaft 16 carries a spur gear 17 that meshes with a spur gear 18 mounted within the said casing 15 and provided on its hub or shaft with a worm 19, which, in turn, meshes with a worm gear 20 on the upper end of the boring tool shaft 10. The upper head of the supporting frame 14 is provided with projecting arms 14^a, the ends of which are seated in pockets afforded by anchoring lugs or castings 21 above stop rings 21^a secured on the interior of the lower tube section.

As is evident, when the boring tool is rotated by means of the electric motor, it will loosen up and slightly elevate the dirt from below the lower end of the foundation tube. To pick up and elevate this loosened dirt so that the tube may be lowered and caused to follow the boring tool, we provide an endless elevating belt, preferably in the form of one or more sprocket chains 22 equipped with elevator pockets 23. This sprocket chain 22 is arranged to run over a lower sprocket 24, over an upper sprocket 25 and over idle guide sprockets 26. The said lower sprocket 24 is an idle sprocket secured to a shaft 27 journaled in suitable bearings on the frame 14. The sprockets 25 and 26 are journaled in upwardly projecting portions 28 of a larger anchoring sleeve 29, which latter is telescoped over the upper end of the upper tube section 1 and is adapted to be rigidly but detachably secured thereto, by set screws 30, or other suitable devices. The shaft 31 of the upper sprocket 25 is preferably extended and driven from a stationary engine, electric motor or other power device located above the ground.

The chain 22 is made up of sections that correspond in length to the length of the tube sections 1, and which chain sections are detachably connected at points marked 22^a. A well known means for connecting sections of the sprocket chains may be employed for this purpose. Obviously, whenever a tube section 1 is added, corresponding chain sections must also be added, for the reason that

the supporting sleeve 29 must always be applied to the upper end of the uppermost tube section, while the motor and boring tool and lower sprocket 24 are carried on downward by the lower tube section. Obviously, the circuit wires 32 should lead to and from the electric motor at the lower end of the tube, but extend upward through the tube connected to a suitable source of electrical current supply. Obviously, the sleeve 29 may be set in different vertical adjustments on the upper tube section 1, so as to take up the slack of the endless chain 22 and so as to permit insertion and removal of chain sections, when desired.

Heretofore may be noted that the upper sprocketed is offset, or at one side of the tube, so that the dirt elevated from the bottom of the tube will be discharged from one side of the upper end of the tube, but, of course, a suitable conveyer or other means may be provided for carrying the dirt away from the tube, as it is delivered from the same.

For lifting the frame 14, the motor and boring tool and other parts carried thereby out of the tube, and for lifting the sleeve 29 and parts carried thereon, when desired, we preferably provide a derrick attachment which may take various forms, but which may be of the arrangement illustrated in Fig. 1, wherein the numeral 33 indicates a windlass drum, the shaft 34 of which is journaled in a suitable bearing on the upper end of a supporting frame 35. A sprocket wheel 36 is secured to the shaft 34, and a sprocket chain 37 runs over this sprocket and over a smaller sprocket, not shown, but which is carried by a short shaft 38 journaled in suitable bearings on the base 5, and provided with a beveled gear 39. The beveled gear 39 meshes with a beveled gear 40 carried by the lower end of a telescopically extensible shaft 41, the upper end of which is provided with a beveled gear 42 that meshes with a beveled gear 43 carried on the hub of the upper sprocket 25. The numeral 44 indicates a pulley secured on the shaft 38, over which a power driven belt, not shown, is adapted to run to impart motion to the said shaft 38, and through the connections described, both to the windlass drum 33 and to the upper sprocket 25, and through the latter, to the elevator chains or belt 22.

When the boring tool and conveyer are in action, the casing 1, in most instances, may be continuously lowered by rotation of the sleeve 3. Of course, from time to time, it will be necessary to loosen the said sleeve on the upper pipe section and screw the same up to a higher point so that its downward forcing action may be repeated over and over again. In the drawings, the said sleeve is shown as if working very close to the

- ground surface, but it may be arranged to work a greater distance above the ground when desired. Anything but large rocks will be guided up by the pockets of the conveyor and carried out of the tube. Very large rocks will have to be removed in some other way. For example, we might employ a large crushing hammer attached to a cable and the cable arranged to work on the drum 5
- 10 33. The use of such a crushing hammer would require that the conveyor, motor, boring tool, and frame 14 be first removed from the tube. Usually, however, such a boring apparatus would be used in boring through sand in search of a strata of foundation rock, and in such use the boring apparatus would work rapidly and with very great efficiency, and could be used to sink foundation tubes to a very great depth. 15
- 15 20. When the motor supporting frame 14 with the motor and boring tool are lowered into the tube, the projecting ends of the upper bar 14^a will strike upon the ring 21^a and limit the downward movement thereof. 20
- 20 25. By backward rotation of the said frame, that is, by rotation thereof in a direction reverse to the direction in which the boring tool is operatively rotated, the ends of the bar 14^a will be driven tightly into the pockets afforded by the lugs or castings 21 and the underlying portions of the ring 21^a. The lower portion of the frame 14 is so cut away that it will clear or pass through the ring 21^a. 30
- 30 35. From a broad sense, the apparatus described is a boring apparatus adapted for general use, and in addition to the uses above noted, it may be stated, that it is also well adapted for use in sinking well tubes. 35
- 40 40. The apparatus will work even where the tube is more or less filled with water, and this adapts the said apparatus for use in sinking tubes through quick sand where ordinary apparatus cannot be used at all. 45
- 45 1. What we claim is:
1. The combination with an extensible sectional foundation tube having means for detachably connecting the sections thereof, of a motor applied to the lower tube section, a motor driven boring tool working below said tube, an extensible conveyor working in said extensible tube, a support for the upper portion of said conveyor, applied to the upper tube section, and connections for driving said conveyor. 50
  2. The combination with an extensible sectional foundation tube having means for detachably connecting the sections thereof, of a motor applied to the lower tube section, a motor driven boring tool working below said tube, an extensible conveyor working in said extensible tube, a support for the upper portion of said conveyor applied to the upper tube section, a relatively fixed base support, and connections between said base 55
- support and said sectional tube for forcing the same and the parts carried thereby, bodily downward. 3. The combination with an extensible sectional foundation tube having means for detachably connecting the sections thereof, of a motor applied to the lower tube section, a motor driven boring tool working below said tube, an extensible conveyor working in said extensible tube, a support for the upper portion of said conveyor applied to the upper tube section, a relatively fixed base support, and connections between said base support and said sectional tube for forcing the same and the parts carried thereby, bodily downward, and means for driving said conveyor, comprising a driving wheel on said base support, a driven wheel on said conveyor support, and a telescopic extensible driving shaft connecting said driving and driven gears, and serving to transmit motion to said conveyor in different adjustments of the said sectional tube. 70
- 75 4. The combination with a foundation tube, of a motor in the lower end of said tube, an extensible motor driven boring tool working below the lower end of said tube, and co-operating interlocking devices on said motor support and the interior of the lower section of said tube arranged to be interlocked by rotation in a direction reverse from the operative direction of rotation of said boring tool and to be separated when said motor support is rotated in the other direction, whereby the said tool, motor and support may be detached from and moved upward out of said tube. 80
- 85 5. The combination with a sectional foundation tube having means for detachably connecting the sections thereof, of a motor detachably connected to the lower section of said tube, a motor-driven boring tool working below said tube, an extensible conveyor working in said tube, a support in the upper end of said conveyor detachably applied to the upper tube section, and means for driving said conveyor. 90
- 95 6. The combination with a sectional foundation tube and means for connecting the sections thereof, of a motor applied to the lower foundation section, a boring tool below said tube operated by said motor, a sleeve detachably secured to the upper end of the upper tube section, conveyor guides on said sleeve, conveyor guides mounted on the lower end of the lower tube section, and an endless conveyor running through said tube and over said conveyor guides. 105
- 110 7. The combination with a sectional foundation tube and means for connecting the sections thereof, of a motor applied to the lower foundation section, a boring tool below said tube operated by said motor, a sleeve detachably secured to the upper end of the upper tube section, conveyor guides 115
- 120 8. The combination with a sectional foundation tube and means for connecting the sections thereof, of a motor applied to the lower foundation section, a boring tool below said tube operated by said motor, a sleeve detachably secured to the upper end of the upper tube section, conveyor guides 125
- 130

on said sleeve, conveyer guides mounted on the lower end of the lower tube section, an endless conveyer running through said tube and over said conveyer guides, the upper 5 portion of said conveyer being offset to one side of said tube whereby the elevated earth will be discharged outward of said tube.

In testimony whereof we affix our signatures in presence of two witnesses.

HENRY SLETTEN.

ALEXANDER N. LIDELL.
